UNITED STATES PATENT OFFICE.

HOMER S. ROGERS, OF MILWAUKEE, WISCONSIN, ASSIGNOR TO JOHN R. BALL, OF MILWAUKEE, WISCONSIN.

PNEUMATIC PUMP.

1,274,332.

Specification of Letters Patent.

Patented July 30, 1918.

Application filed December 1, 1916. Serial No. 134,226.

To all whom it may concern:

Be it known that I, HOMER S. ROGERS, a citizen of the United States, residing at Milwaukee, in the county of Milwaukee and

5 State of Wisconsin, have invented certain new and useful Improvements in Pneumatic Pumps, of which the following is a specification, reference being had to the accompanying drawing, forming a part thereof.

10 This invention relates to pneumatic pumps and the objects of the invention are to improve pneumatic pumps in the manner to be hereinafter described and claimed.

Referring to the drawing which accompanies this specification and forms a part hereof, which drawing illustrates an embodiment of this invention, the illustration is a vertical section of a pneumatic pump.

Referring to the drawing, the reference 20 numeral 1 designates a base which is provided with a water inlet valve 2 and a water outlet valve 3. The top 4 is provided with an air exhaust port 5, an air inlet port 6, a guide 7 and a standard 8. The base 1 and 25 the top 4 are connected by a casing 9 to form a pump chamber 10. The reference numeral 11 designates the water outlet pipe and 12 the compressed air inlet pipe. A

30 fluid actuated motor is formed by the diaphragm 13 and the cap 14 and the cap 14 is provided with the bleed vent 15. A pipe 16, of greater area than the bleed vent 15, communicates with the space between the diaphragm 13 and cap 14 and preferably has 35 its lower end extending below the low water level in the pump chamber 10 so that it will be water sealed at all times. A valve 17 which is actuated by the float 18 controls the communication between the pump chamber 10 and the fluid actuated motor. This

40 valve 17 is closed by the buoyancy of the float 18 but the float need exert no great buoyancy as the valve is kept closed by the difference between the pressure in the pump 45 chamber 10 and the pressure in pipe 16. This difference in pressure will keep the valve 17 closed, as the water level falls in the pump chamber 10, until so much of the float 18 is out of water that its weight will 50 overcome the pressure keeping the valve 17 closed. The float 18 will then drop, or sink in the water quickly and pop the valve 17 open suddenly, because the pressures on opposite sides of the valve 17 will be equalized and the float 18 and valve 17 can fall by

gravity until the float has sunk to its line, or plane, of flotation.

The air exhaust port 5 is controlled by an exhaust valve 19 which is guided by the pivoted lever 20. The air supply valve 21 60 is closed by the lever 20 and is opened by gravity and the pressure of the compressed air.

The weighted float valve 19 should be 65 buoyant enough to be floated up against its seat by the water and should be light enough to be held against its seat by the difference between the pressure in the pump chamber 10 and the pressure in the exhaust port 5.

The exhaust valve 19 is referred to as a 70 weighted float valve because it must be heavy enough to close the air valve 21 by lifting its weight and overcoming the pressure of the compressed air upon it, yet must be light enough to float in the water and light 75 enough so that the difference between the pressure of the air in the pump chamber 10 and the pressure in the exhaust port 5 will keep the valve seated.

A plunger 22 is normally held in an elevated position by a spring 23 but can be forced down by the diaphragm 13 to force the float valve 19 away from its seat to open the exhaust port 5.

The operation of the pump is as follows: 85 The parts are shown by the drawings in the positions which they occupy when the water is being forced out of the pump chamber 10. When the water level falls sufficiently below the top of the float 18 so that the 90 weight of the float overcomes the pressure which is keeping the valve 17 closed, the valve 17 will be opened quickly, water will be forced suddenly through the pipe 16 and force the diaphragm 13 and the plunger 22 95 down and force the weighted float valve 19 away from its seat whereby the pressures on its opposite sides will be equalized and it will drop closing the air valve 21 and permitting the compressed air in the pump 100 chamber 10 to exhaust. The water outlet valve 3 will be closed by its spring and the water inlet valve 2 will open as water flows into the pump chamber 10. As the water 105 fills the pump chamber 10, the float 18 will rise and close valve 17. The spring 23 will raise the plunger 22 and the diaphragm 13 forcing water out through the bleed vent 15. As the water level continues to rise in the pump chamber 10, the weighted float 110

valve 19 will be raised toward its seat and the air valve 21 will be opened permitting compressed air to rush into the pump chamber 10. If the weighted float valve 19 has not quite reached its seat, the rush of compressed air trying to escape through the exhaust port 5 will seat the valve firmly.

The exhaust port valve 19 has been referred to as weighted and it will, of course, be understood that its weight must be sufficient, when multiplied by the leverage of the lever 20, to close the compressed air valve 21, and keep it closed, against the pressure exerted by the compressed air.

15 When the exhaust port 5 is open, the spring 23 will lift the plunger 22 and the diaphragm 13 and force water out of the pipe 16 into the pump chamber 10, but the bleed vent 15 also provides for the escape 20 of water and provides a vent for any air which may separate from the water.

What is claimed is:

1. In a pneumatic pump, the combination with a pump chamber, provided with 25 water inlet and outlet valves and an air exhaust port, of an air exhaust valve adapted to close the exhaust port when water has filled the pump chamber and adapted to be retained closed by the difference between 30 the pressures in the pump chamber and outside thereof, a compressed air valve, a fluid actuated motor for opening the exhaust valve, and means for causing the motor to open the exhaust valve when the water in 35 the pump chamber has been lowered to a predetermined level.

2. In a pneumatic pump, the combination with a pump chamber, provided with

water inlet and outlet valves and an air exhaust port, of a valve for controlling said 40 air exhaust port adapted to be raised toward its seat by the water and adapted to be retained on its seat by the difference between the pressure of the air on opposite sides thereof, a plunger for forcing said 45 valve from its seat, a fluid actuated motor for operating said plunger, a pipe in communication with said motor and extending below the low water level in the pump chamber so that it will be water sealed at 50 all times, a valve for controlling the flow of water through said pipe, and a float adapted to close said valve by buoyancy and open it by gravity.

3. In a pneumatic pump, the combination with a pump chamber, provided with water inlet and outlet valves and compressed air inlet and exhaust valves, a lever pivoted between the air inlet and exhaust valves so that the compressed air tends to close the 55 exhaust valve, and a fluid actuated motor for opening the exhaust valve and closing the compressed air inlet valve, when the water level in the pump chamber has been lowered to a predetermined level, by the 60 pressure of the compressed air in the pump chamber, the exhaust valve being adapted to be closed as the water level in the pump chamber rises and to be kept closed, as the water level lowers, by the difference between 65 70 the pressures in the pump chamber and outside thereof.

In witness whereof I hereto affix my signature.

HOMER S. ROGERS.
